(57) **CLAIM**

The ornamental design for a display screen or portion thereof with animated graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with animated graphical user interface;

FIG. 2 is a front view of a second image thereof;

FIG. 3 is a front view of a third image thereof;

FIG. 4 is a front view of a fourth image thereof;

FIG. 5 is a front view of another embodiment of a display screen or portion thereof with animated graphical user interface;

FIG. 6 is a front view of a second image thereof;

FIG. 7 is a front view of a third image thereof; and,

FIG. 8 is a front view of a fourth image thereof.

The peripheral dashed broken lines illustrate a display screen or portion thereof and form no part of the claimed design.

The text illustrated in broken lines forms no part of the claimed design.

The claimed design is illustrated within the interior dashed line circles or rectangles; the portions between the peripheral dashed broken lines and the interior dashed line circles or rectangles form no part of the claimed design.

The appearance of the graphical user interface transitions sequentially between the images shown in FIGS. 1-4 and FIGS. 5-8. The process or period in which one image transitions to another forms no part of the claimed design.
